UNITED STATES PATENT OFFICE.

FRED ALLEN SHONTZ, OF EUREKA, UTAH.

ADJUSTABLE PLANE-HANDLE.

SPECIFICATION forming part of Letters Patent No. 790,533, dated May 23, 1905.

Application filed July 27, 1904. Serial No. 218,420.

To all whom it may concern:

Be it known that I, FRED ALLEN SHONTZ, a citizen of the United States, residing at Eureka, in the county of Juab and State of Utah, have invented a new and useful Improvement in Adjustable Plane-Handles, of which the following is a specification.

This invention is an adjustable handle for planes, and while capable of use in connection with any construction of plane is preferably employed in connection with the rabbet-plane having a metal base.

The object of the invention is to provide a plane having a laterally-adjustable handle, so that the said plane can be conveniently used in positions where it would be inconvenient to use a plane with a non-adjustable handle, owing to the hand of the operator coming in contact with the work being operated upon.

The invention consists in the novel features of construction and combination of parts hereinafter fully described, and pointed out in the claims.

In the drawings forming a part of this specification, Figure 1 is a sectional elevation illustrating my invention. Fig. 2 is an end view of the plane provided with my improved form of handle, the dotted lines showing the different adjustments of the handle. Fig. 3 is a sectional view taken through the handle. Fig. 4 is a detail perspective view of the block to which the handle is connected.

In carrying out my invention I employ a plane A, the base A' of which is provided with an essentially rectangular-shaped boss B, to which is secured a block C, essentially semicircular in cross-section, the bottom face of said block being cut away intermediate the ends, as shown at C', in order to fit snugly upon the boss B. Screws D and D' are employed for securely connecting the block C to the boss B on the base of the plane. E indicates the handle, which is shaped substantially the same as the ordinary handle, said handle being connected to the block C by means of brackets F and G, having journal or pivot portions F' and G', which engage the bearing-recesses C', formed in the lower face of the end portions of the block C. The han-

dle E has a bore H extending from the upper 50 to the lower end thereof, the upper portion of said bore being of greater diameter than the lower portion, and working in said bore is the locking-rod I, having a pin K passed transversely therethrough, and bearing upon 55 said pin is a spiral spring L, the normal tendency of which is to project the lower end of the rod through the handle and into engagement with one of a series of oblique openings M, formed radially in the periphery of the 60 block C, thereby locking the handle in either a central or a right or left position. The upper end of the spring L engages the tubular plug N, fitted in the upper end of the bore H, and a thumb-lever O is pivoted at O' to the 65 top of the handle E and is pivotally connected at O'' to the upper end of the rod I, and by pressing downwardly upon said thumb-lever the said rod is drawn up into the handle, so as to disengage its lower end from the opening M, and the handle can then be adjusted to the desired position and the rod will be thrown into engagement with the block by means of the spring L. It will thus be seen that I provide an adjustable handle and means 70 for connecting the same to the base or stock of the plane, and it will be noted that said handle and its attaching means are capable of use in connection with any of the ordinary construction of planes now in use.

Having thus fully described my invention, what I claim as new, and desire to secure by Letters Patent, is—

1. A plane having a block secured to its base, a handle having brackets connected to 85 the opposite ends thereof, said brackets being pivotally connected to the ends of the block, said block having a series of openings arranged at different angles, a spring-actuated locking-rod arranged in the handle and adapted to engage the said openings and means for raising said locking-rod as set forth.

2. A plane, the base of which is provided with a boss, a block semicircular in cross-section, recessed upon its lower face, and secured 95 to the boss, the opposite ends of said block having bearing-recesses, a handle having a bore extending therethrough, a spring-actu-

ated rod arranged in said bore and provided with a thumb-lever for raising the said rod, the block having a series of openings arranged upon different angles and adapted to be engaged by the lower end of the locking-rod, and brackets attached to the ends of the handle and provided with journals adapted to engage

the bearing-recesses in the ends of the block, as set forth.

FRED ALLEN SHONTZ.
